UNITED STATES PATENT OFFICE

142,053

DESIGN FOR AN EDUCATIONAL TOY FOR TEACHING ARITHMETIC

David Wurster, New York, N. Y., assignor to Jack
Bergman, Pittsburgh, Pa.

Application April 24, 1945, Serial No. 119,168

Term of patent 14 years

(Cl. D25—1)

To all whom it may concern:

Be it known that I, David Wurster, a citizen of the United States, residing in New York, in the county of New York and State of New York, have invented a new, original, and ornamental Design for an Educational Toy for Teaching Arithmetic, of which the following is a specification, reference being had to the accompanying drawing, forming part thereof.

The figure is a perspective view of an educational toy for teaching arithmetic, showing my new design.

I claim:

The ornamental design for an educational toy for teaching arithmetic, as shown.

DAVID WURSTER.
